LOCOMOTIVE SUPERHEATER

Application filed April 20, 1927. Serial No. 185,100.

This invention relates to locomotive superheaters, and has for its primary object and purpose to provide an improved arrangement of the superheater header and elements whereby a very high degree of superheat may be obtained with a minimum fuel consumption, less loss in steam pressure between boiler and valve chests, a lesser amount of superheater heating surface and with greater accessibility to the superheater header and elements for inspection and cleaning.

Heretofore, with the conventional arrangement of the superheater in relation to the locomotive boiler, the superheater header has been located at the front end of the boiler with the saturated and superheated steam conducting elements or tubes projecting rearwardly into the fire tubes of the boiler for the greater portion of the length of the latter. It is usual to arrange the superheater header in the smoke box, and when the boiler fire tubes and flues become obstructed by honey-comb, ashes and other foreign material, they must be blown out from the fire box end of the boiler. This requires that a specially constructed flue blowing or cleaning device be installed in the fire box, or on the other hand, that the fire be dumped and the locomotive cooled in order that a man may enter the fire box for the purpose of blowing out and cleaning the flues. We propose to obviate this difficulty by mounting and arranging the superheater header at the fire box end of the boiler. The front ends of the fire tubes and flues are thus left unobstructed so that they can be readily blown out from the front end of the boiler without cooling the locomotive by merely opening the smoke box door and inserting the flue blowing device, through the door opening for the cleaning process.

It is also another object of the invention to provide a mounting and arrangement of the superheater at the fire box end of the boiler and adjacent the rear end thereof where the superheater header will be directly subjected to the high temperature gases and the generated heat most economically utilized both in the production of saturated

steam in the boiler and in the production of superheated steam.

It is a further object of our present improvements to provide a mounting and arrangement of the superheater and the superheater elements which will operate somewhat in the manner of a radiant heat type of superheater, but which will possess the advantage that the fuel bed or particles of the solid burning fuel need not come into direct contact with the superheater header or elements or other parts.

With the above and other objects in view, our invention consists in the improved locomotive superheater and in the mounting and relative arrangement of the several parts thereof with respect to the locomotive boiler and fire box as will be hereinafter more fully described, illustrated in the accompanying drawings, and subsequently incorporated in the subjoined claims.

In the drawings, wherein we have illustrated one application of our present invention to a type of boiler as used in connection with high powered steam locomotives, and in which similar reference characters designate corresponding parts throughout the several views,—

Figure 1 is a fragmentary longitudinal section through the locomotive boiler and fire box showing our improved superheater installation;

Fig. 2 is a transverse sectional view taken on the line 2—2 of Fig. 1, and

Fig. 3 is a fragmentary vertical sectional view similar to Fig. 1, more particularly illustrating the mounting and arrangement of the superheater header with relation to one form of fire box construction.

Referring in detail to the drawings, for purposes of illustration, we have shown the rear vertical water leg 5 of a fire tube boiler, spaced upper steam drums 6 and the spaced lower drums 7 arranged at opposite sides of the fire box generally indicated at 8, said lower drums being connected with the upper drums at opposite sides of the fire box by means of the vertical banks of tubes 9. It will however, be understood that the particular type of boiler illustrated in the draw-

ings is not essential and that the present invention is of general application to any type of fire tube boiler and may also be employed in connection with boiler furnaces 5 utilizing coarse or pulverized coal or lignite, gas, oil, or other solid, liquid, or gaseous fuels.

As herein shown, the superheater header 10 is located within the fire box 8, preferably adjacent to the fire box flue sheet constituting the rear wall of the water leg 5 and below the fire tubes or flues 11. The superheater header may be located in any other convenient place, for example, at the top or 10 sides of the fire box or it may be subdivided into two or more parts differently or similarly located from which the superheater elements may enter the fire flues of the boiler. This header 10 is formed with the usual 15 saturated and superheated steam receiving chambers with which the ends of the superheater elements 12 are suitably connected. These superheater elements are each in the form of a tube bent to provide a single elongated loop 13 which extends into the rear end of one of the fire tubes or flues 11 and to a point adjacent the forward end thereof. These elements may, however, be of 20 double loop type, spiraled or of any other 25 form of fire flue superheater element.

To one part of the superheater header 10, the saturated steam supply pipe 14 from the boiler is connected while the superheated steam receiving pipe 15 is connected to another part of the header and is adapted for 30 connection with the steam chests of the locomotive cylinders in any approved manner. Separate headers may be used for each of the 35 saturated and superheated steam connections.

In Fig. 3 of the drawings, we have shown the superheater header 10 arranged between the fire box flue sheet and the vertically positioned protection plate 16 and preferably 40 below the fire box grate. Upon the upper end of this protection plate the forward end of the arch wall is supported as in Fig. 1 of the drawings. The superheater elements 12 extend upwardly from the header 10 closely 45 contiguous to the metal plate 16. The plate 16 thus protects the header and the superheater elements as well as the joint connections therebetween from the direct influence 50 of the fire in the fuel bed and also prevents short circuiting of the products of combustion through the superheater elements to the fire tubes without first passing around the rear end of the combustion chamber baffle wall. The saturated and superheated steam 55 conducting pipes 14 and 15 may be connected to the superheater header by the conventional joints indicated at 17, which in the arrangement shown are easily accessible for the purpose of inspection and repair.

60 In each of the arrangements illustrated

in the drawings, on account of the heat absorbing qualities of the metal protection plate, or of the fire brick wall which may be placed between the superheater header and elements and the fuel bed, and owing to the 65 heat absorbing qualities of the superheater header and elements, a larger percentage of high temperature heat is extracted from the fuel consumed than is possible with the conventional arrangement of the superheater header in the smoke box or other relatively 70 low temperature zone. This high temperature absorbed heat will tend to add to the degree of superheat taken on by the saturated steam in its passage through the superheater elements, in contradistinction to the giving off or loss of a part of the superheat 75 in the conventional arrangement of the superheater in the flow of the steam through the superheater elements and the header between the saturated and superheated steam pipe connections with the latter.

From the foregoing, it will be apparent that as the superheater header is located in the hottest zone at the fire box end of the 80 boiler, a very high degree of superheat may be obtained with economy in fuel consumption. Also, owing to this location of the superheater, we are enabled to use the single 85 loop elements 12 extending into the fire flues 90 so as to reduced obstruction of the flues to a minimum as well as the resistance to the flow of the steam passing through said superheater elements. At the same time, the superheat accumulated by the steam and the pressure 95 at which this superheated steam enters the steam chests of the cylinders will be appreciably greater than has heretofore been obtained, thus resulting in a material increase in power output and thermal efficiency 100 of the locomotive and with greater economy 105 than has heretofore been possible.

By the location of the superheater elements rearwardly of the fire box flue sheet, these elements will act as a screen protecting the flue sheet from the collection of honey-comb and other foreign matter which tends to obstruct the draft through the fire tubes or flues. However, when it becomes necessary to clean out these flues, this may be readily done by inserting the flue blower through the smoke box door at the forward end of the boiler and delivering the blower pressure into the forward ends of the tubes. Thus, it is not necessary to install a special tube 110 cleaning device in the locomotive fire box or on the other hand, dump the fuel bed and cool the fire box and frequently remove arch brick so that a man may enter the same and blow or otherwise clean out the tubes.

In the arrangement of the superheater at the front end of the boiler inside of the smoke box, or on the top thereof where it must be properly insulated, accessibility is difficult. With our invention, by locating the super-

heater either within the fire box or above or below the same at the rear end of the boiler, it becomes more accessible for inspection, cleaning and repairs. Also with the conventional arrangement of locomotive superheaters where the superheater elements are connected with the header inside of the smoke box, in the event that leakage occurs at these joint connections, the escaping steam interferes with the vacuum in the smoke box and consequently with the draft through the fire tubes and the production of steam. In our present invention, these joints being located at the fire box or outside of the smoke box, should any leakage occur, it will not affect the draft through the fire tubes so that the draft will not be affected and fuel consumption will not be increased in order to maintain the necessary steam pressure.

In the existing arrangement of superheaters where the superheater elements project into the forward ends of the fire tubes, in order to secure a sufficient degree of superheat, it is necessary to provide superheater elements of the so-called double loop type and to make these double loop superheater elements almost as long as the fire tubes into which they project. This not only seriously obstructs passage of the gases through the fire tubes but also increases frictional resistance to the steam passing through the superheater elements and substantially reduces the boiler pressure before the superheated steam reaches the engine cylinders. As above noted, we provide preferably a single loop superheater element extending into the rear ends of the fire tubes. With the present arrangement of the double loop superheater element extending into the front end of the fire tube, it is apparent that such construction and arrangement is very inefficient, as the final passage of the steam through the superheater element to the header travels from a hot zone at the rear end of the fire flue to a relatively cold zone at the forward end thereof and the steam therefore, necessarily, in its final pass, gives off and does not take on superheat. Also, in order to secure economically a high degree of superheat, it is not possible to obtain the full benefit of the combustion temperature in the fire box and maintain a sufficiently high evaporative capacity to produce saturated steam in the boiler without maintaining an uneconomically high temperature in the boiler smoke box. With our invention however, the final passage of the steam in the superheater element is from a relatively cold zone to a comparatively hot zone at the fire box end of the boiler. It therefore, becomes possible to secure a very high degree of superheat and with a simpler form of the superheater elements without maintaining an abnormally high temperature in the smoke box. The superheater headers and elements are usually made of iron or steel casting or plates

or of cold or hot drawn seamless steel tubing, but we propose when advisable or necessary, to produce these headers and elements from high heat resisting alloys. Several such alloys have been developed in recent years. For instance, those alloys exploited under the trade names of "ascoloy", "duralloy", "fabrite", "thermalloy", "hardite", "Beckett metal", and "Elesco metal" are suitable for such purpose.

By enabling a substantial reduction in the smoke box temperature to be maintained by means of our invention, a greater proportion of the heat generated may be utilized for the purpose of evaporation to produce saturated steam in the boiler. Also the use of dead plates, baffle plates, dampers and other draft retarding appurtenances heretofore necessary in the smoke box on account of the location of the superheater header and elements at that point may be eliminated, thus making it possible to appreciably enlarge the locomotive cylinder exhaust nozzle and thereby reduce the cylinder back pressure and the loss of power in the engine while producing the necessary draft for combustion. This also of course, renders the boiler flues and tubes more accessible for the purpose of cleaning and obviates the necessity of dumping the fuel bed and removing arch brick and other parts from the fire box as is the present practice in order to blow out the tubes from the fire box end of the boiler.

Heretofore, it has been a very time consuming and expensive matter to make necessary repairs to the superheater or any part of the boiler connected therewith, owing to the necessity of first removing the various appliances or accessories from the smoke box. With our invention, it is a simple and easy matter to disconnect the superheater elements from the header and remove them from the fire tubes through the fire box without entering the smoke box or in any way disturbing the appliances therein.

Preferably, in practice, we will arrange all of the superheater elements substantially as shown in the drawings at the rear end of the locomotive boiler adjacent the fire box flue sheet and connect them with a single header. However, if desired, a superheater header may be arranged at the front end of the boiler and a number of superheater elements connected therewith and extended into the upper fire flues while the remaining superheater elements are connected with a separate header at the fire box flue sheet and extended into the lower fire flues. Of course with this arrangement, suitable means will be provided for connecting the saturated and superheated steam pipes leading respectively to and from the different superheater headers to the locomotive boiler and the engine cylinders respectively.

From the foregoing description consid-

ered in connection with the accompanying drawings, it is believed that the construction and relative arrangement of the several parts of our invention as well as the numerous advantages to be derived therefrom will be clearly and fully understood. Of course, it is apparent that in so far as the fundamental feature of our present disclosure residing in the new location or arrangement of the superheater with respect to the locomotive boiler is concerned, other forms of the superheater elements as well as other forms or constructions of the superheater header might be employed. Also, it will be apparent that if desired, the superheater header might be mounted and arranged above the fire tubes or flues so that the superheater elements will extend downwardly therefrom and into the respective tubes, instead of the reverse arrangement as shown in the drawings. Accordingly, it is to be understood that in the application of our invention to various different types of fire tube boilers, numerous alternatives in the form and construction of the several parts as well as the specific location and mounting thereof relative to the fire tubes as herein illustrated might be resorted to, and we therefore, reserve the privilege of adopting all such legitimate changes therein as may be fairly incorporated within the spirit and scope of the invention as claimed.

We claim:

1. In combination with a locomotive fire tube boiler and fire box and a vertically positioned protection wall at the front end of the fire box in spaced relation to the fire tube flue sheet, a superheater header mounted between said protection wall and the flue sheet below the open ends of the fire tubes, and superheater elements connected with said header and having parts positioned contiguous to said protection wall and extending forwardly into the fire tubes.
2. In combination with a fire tube boiler and a fire box, a superheater header mounted adjacent to the boiler flue sheet and below the path of flow of the products of combustion.
3. In combination with a locomotive fire tube boiler and a firebox having an end wall spaced from the adjacent boiler flue sheet, a superheater header mounted in the space between said firebox wall and flue sheet and below the zone of fuel combustion, and superheater elements connected to said superheater header extending upwardly through said space and forwardly into the boiler fire tubes.
4. In testimony that we claim the foregoing as our invention, we have signed our names hereto.

JOHN E. MUHLFELD.
JOHN C. CHAPPLE.
